A. E. GERTSFELD

LOCK

Filed July 7, 1925

Inventor
Abraham E. Gertsfeld
By his Attorney
Harry Radzinoff

UNITED STATES PATENT OFFICE.

ABRAHAM E. GERTSFELD, OF NEW YORK, N. Y.

LOCK.

Application filed July 7, 1925. Serial No. 41,942.

To all whom it may concern:

Be it known that I, ABRAHAM E. GERTSFELD, a citizen of the United States, and a resident of the city of New York, county of Bronx, and State of New York, have invented a new and useful Improvement in Locks, of which the following is a specification.

This invention relates to an improvement 10 in locks of the character adapted for use upon windows, dumbwaiters, closets, doors of various kinds, and the like, and the object of the invention is to provide such a lock which will be simple in construction 15 although extremely strong and sturdy.

A further object of this invention is to provide a lock of the character mentioned which cannot be readily "picked" or broken open.

With these objects, and such other objects as may hereinafter appear in view, I have devised the particular arrangement of parts hereinafter set forth and more particularly pointed out in the claims appended 25 hereto.

Reference is to be had to the accompanying drawing, forming a part hereof, in which

Figure 1 is a plan view of my improved 30 lock;

Figure 2 is an end view of the same;

Figure 3 is an end view of the lock keeper; and

Figure 4 is a sectional view on the line 35 4-4 of Figure 1, looking in the direction of the arrows, the lock in Figure 4 being shown in its open or retarded position.

Throughout the various views of the drawings, similar reference characters 40 designate similar parts.

In the embodiment of my invention as disclosed in the accompanying drawing, 1 indicates the base plate of the lock and 2 indicates the base plate of the lock keeper.

The base plate 1 of the lock is provided with screw holes 3 which may be positioned as desired so that screws may be passed through them to secure the lock to a door or window, a portion of which is indicated at 21 in Figure 4.

The keeper 2 is provided with screw holes 4 for a similar purpose and said keeper is also provided with a head 5 which has a bore 7 for the reception of the bolt 10 of the lock. To add rigidity and strength to the keeper, I provide it with a downwardly

projecting flange 6 having a screw hole 8 through which a screw may extend to hold the keeper in position. The keeper is thus extremely strong and cannot be very readily 60 pried from the door or window frame 22 to which it is adapted to be secured.

The lock is provided with a tubular bolt-casing 9 through which the bolt 10 is movable. It will be noted that the bolt-casing 65 is open at both of its ends so that when the lock is in its open position, as shown in Figure 4, and the bolt 10 is drawn back or retarded, a part of said bolt is projected out of the back of the casing 9. To enable 70 the bolt 10 to be manually shifted, it is provided with a pin 11 which passes through it, and said pin moves in a slot 13 provided in the upper part of the bolt-casing 9. The upper end of the pin 11 terminates in a head 75 which lies on the outside of the casing 9 so that it may be readily grasped to draw back the bolt against the tension of the spring 20 which surrounds the bolt within the casing and normally tends to thrust the bolt 80 forward and out of the casing and into the bore 7 of the keeper, retaining the same in its "locked" position.

At 16 is shown a lock plate or latch member for the lock, said member consisting of 85 a flat curved plate having one of its ends pivoted on a pin 15 which projects from an ear 14 integrally formed on the casing 9. The other end of the latch member is bent laterally as at 17 and said laterally bent portion frictionally engages with a hook-shaped catch 18 on the plate 1, said portion 18 being preferably formed by bending upwardly a portion of the base plate 1.

It will be seen that when the lock is in its 90 closed position, with the bolt 10 projected out of the front of the casing, as disclosed in Figure 1, and the latch member 16 is in its closed position, as indicated clearly in Figure 2, the bolt cannot be forced backward as 100 its rear end bears against the face of the latch member 16, which is so shaped that it partly closes the back opening of the bolt-casing 9. It will thus be apparent that the lock can only be opened by a person on the 105 inside who can manually raise the pivoted latch-member 16 to the position indicated in dotted lines in Figure 2 to permit the bolt to pass out through the back of the casing when the knob 12 is pressed.

To hold the lock in its open position, as indicated in Figure 4, wherein the bolt 10 is

held in a retarded position within the casing, I provide the upper face of the bolt 10 with a transverse slot 19 into which the latch member 16 can be moved. The lock can, by the means just described, be indefinitely held in its open position, until the latch member 16 is manually lifted out of the slot 19 to permit the spring 20 to act to force the bolt 10 outwardly and into the bore 7 of the keeper.

The latch member 16 is therefore utilized to hold the bolt in its locked or open position by acting as an abutment against the end of the bolt or by engaging with the slot 15 placed in said bolt.

Having described my invention, what I claim is:

1. An article of the class described comprising a lock casing, a spring pressed bolt 20 therein, said bolt being capable of having its rear end moved out of the back of the casing, a hinged member adapted to act as an abutment against the rear end of the bolt to prevent such movement, said bolt being provided with a transverse slot into which the hinged member may be positioned when a portion of the bolt has been projected out of the casing.

2. An article of the class described comprising a lock having a flat base plate, a tubular bolt-casing thereon, said casing being provided with two open ends, a bolt movable in said casing, a curved latch-plate hinged adjacent to one of the open ends of the casing, said latch-plate being provided with a laterally bent end, a hook member on the base plate adapted to frictionally engage said laterally bent end to hold the latch plate across one of the ends of the casing, and a slot in the bolt into which the latch plate 40 may be placed to cause the bolt to be held in a retarded position within its casing.

3. An article of the class described comprising a lock casing, a bolt movable therethrough, a spring for normally thrusting the front of said bolt out of its casing, a flat plate hinged at the back of said casing, means for holding said plate across the back of said casing so that one of the faces of said plate partly closes the same, and a slot 50 in the bolt into which the edge of the plate is adapted to fit when a part of the bolt is extended out of the back of the casing.

Signed at the city, county and State of New York, this 3rd day of July, 1925.

ABRAHAM E. GERTSFELD.
